CLAIM

The ornamental design for a cap, as shown and described.

DESCRIPTION

FIG. 1 is an elevated perspective view of a cap showing the new design.

FIG. 2 is a front plan view of the cap of FIG. 1.

FIG. 3 is a first side plan view of the cap of FIG. 1.

FIG. 4 is a second side plan view of the cap of FIG. 1.

FIG. 5 is a back plan view of the cap of FIG. 1; and,

FIG. 6 is a top plan view of the cap of FIG. 1.

Portions of FIGS. 1-5 are shown in dashed lines for illustrative purposes only and form no part of the claimed design.
